(57) **CLAIM**

The ornamental design for a jar opener, as shown and described.

DESCRIPTION

FIG. 1 is a perspective view of the jar opener showing our new design, a friction pad connected to an opening device of the jar opener;

FIG. 2 is a front elevation view FIG. 1;

FIG. 3 is a rear elevation view FIG. 1;

FIG. 4 is a right side elevation view FIG. 1;

FIG. 5 is a left side elevation view FIG. 1;

FIG. 6 is a top plan view FIG. 1; and,

FIG. 7 is a bottom plan view FIG. 1.

The broken lines in the drawings depict portions of the jar opener that form no part of the claimed design.

1 Claim, 5 Drawing Sheets
